UNITED STATES PATENT OFFICE.

GEORGE ORTGIER, OF EAST ST. LOUIS, ILLINOIS.

AEROPLANE.

1,397,292.

Specification of Letters Patent.

Patented Nov. 15, 1921.

Application filed June 1, 1920, Serial No. 385,588. Renewed October 5, 1921. Serial No. 505,568.

To all whom it may concern:

Be it known that I, GEORGE ORTGIER, a citizen of the United States, and resident of East St. Louis, and State of Illinois, have 5 invented certain new and useful Improvements in Aeroplanes, of which the following is a specification containing a full, clear, and exact description, references being had to accompanying drawings, forming a part 10 thereof.

My invention relates to improvements in aeroplanes, and has for its primary object the construction of an aeroplane which is provided with a steering plane at its rear 15 end, and which may be controlled or adjusted to direct the plane in any direction.

In the drawings:

Figure 1 is a top plan view of my improved aeroplane.

20 Fig. 2 is a side elevation of the rear portion thereof, parts being in section.

Fig. 3 is a rear elevation, showing the steering plane in its maximum adjustment while the plane is in flight for descending 25 toward the right.

Fig. 4 is the rear elevation of the machine in flight, and illustrating the steering plane in its maximum adjustment, ascending toward the right.

30 Fig. 5 is the top plan view with parts broken away, illustrating the position of the steering lever when the steering plane is adjusted, as illustrated in Fig. 3.

Fig. 6 is a similar view illustrating the 35 steering lever when the steering plane is in the adjustment as illustrated in Fig. 4.

Fig. 7 is a transverse section taken on the line 7—7 of Fig. 1, when the guiding plane is extended and in use.

40 Fig. 8 is a similar view, illustrating the guiding plane in inoperative position.

Fig. 9 is a transverse section, taken on the line 9—9 of Fig. 2, and Fig. 10 is a side elevation of the steering lever and the parts 45 to which it is attached broken away.

Referring to the drawings:

10 indicates the supporting plane, which may be constructed in any suitable manner.

11 indicates the front portion of the machine and 12 the rear portion and 13 the aviator's seat.

14 indicates the guiding plane which is mounted so as to be adjusted at various angles to the horizontal for guiding and 55 steering the plane in any desired direction.

The rear portion 12, of the plane is formed

hollow and has its rear end closed by means of a member 15, which is formed in two sections, each section being secured to the body portion 12, by means of rivets or bolts 60 16. When the two sections 15, are connected as described, an opening 17, is provided in which the stem or shank 18, of the steering plane is located. The opening 17, and stem 18, being so arranged and proportioned that 65 this stem may move upwardly and downwardly therein, and also rotate. Mounted in the rear portion 12, is a bracket 19; carried by the bracket 19, is a head 20, which is connected to the bracket by universal 70 joint or connection 21. Formed integral with the stem 18, is a member 22, provided with arms 23 and 24; mounted on the head 20, is a steering lever 25, which is free to move forwardly and rearwardly on a pin 75 25^a. By means of the universal joint 21, the head 20, may be rotated, and the steering lever 25 can be moved laterally. Mounted in the member 22, is an end piece 26, the same being secured to the member 22, 80 by means of pins 27, mounted in slots 28, formed in the member 22. Connecting the head 20, and the end piece 26, is a skeleton member 29, formed of strips of light metal, riveted together so as to form a lattice work 85 member. This member 29, is so constructed that it is very light and strong. 30 indicates a link which is pivotally connected to the arm 23 and the steering lever 25; and 31 indicates a similar link which is pivotally 90 connected to the arm 24, and also the lower end of the steering lever 25. By means of this connection, by pushing forward on the steering lever, the steering plane 14, can be elevated as illustrated in dotted lines in 95 Fig. 2, and by the opposite movement of the lever 25, the steering plane may be tilted downwardly as is also illustrated in Fig. 2.

As previously pointed out the head 20, may partly rotate in the bearing 21, and by 100 operating the hand lever laterally the steering plane 14, may be adjusted laterally toward the horizontal.

In Fig. 3 I have illustrated the maximum adjustment of the steering plane when the 105 machine is in flight, in descending toward the right; and in Fig. 4 I have illustrated the maximum adjustment ascending toward the right.

It is understood of course, that by the 110 construction shown and described, the steering plane 14, may be brought to different

adjustments which can be performed by the manipulation of the single steering lever 25.

Mounted in the rear portion 12, of the machine, in a suitable slot provided therefor, 5 is a guiding plane 32, which is pivotally connected and arranged to rotate with the member 29.

In Fig. 7 I have shown the guiding plane 32 in an operative position, occupying the 10 vertical position; and in Fig. 8 it is shown in an inoperative position.

This plane is used when it is desired to fly straight in a horizontal direction, so as to steady the machine. The downward movement of this guiding plane 32, is limited by 15 stop arms 33.

The operation of my improvement is as follows:

In flight in horizontal direction the steering plane 14 is adjusted as shown in solid lines in Fig. 3, by means of the steering lever 25, if it is desired to descend toward the right, and by means of this lever said plane is adjusted as illustrated in dotted lines in 25 Fig. 3, if it is desired to descend toward the left. If it is desired to ascend while in flight, toward the right, the plane is adjusted as illustrated in Fig. 4; and to ascend toward the left, as shown in dotted lines in 30 Fig. 4.

It will be observed that by pushing the lever 25 forward and toward the side to the right two movements or adjustments are given to the plane 14; that is to say, it is tilted forwardly and simultaneously laterally, and if said lever is pushed forwardly and simultaneously to the left, the plane is tilted upwardly and forwardly and simultaneously inclined laterally toward the left.

40 Having fully described my invention what I claim is:

1. An aeroplane comprising a body portion and rear tubular portion, a partially rotating rigid skeleton member located within 45 the tubular portion having one end pivotally mounted therein, a hand lever pivotally connected thereto, a guiding plane mounted in the rear end of the rear portion and pivotally connected to one end of the skeleton 50 member and capable of vertical and lateral adjustment, and a connection between said guiding plane and hand lever whereby the said guiding plane may be vertically and laterally adjusted simultaneously.

55 2. An aeroplane comprising a tubular portion, a rotating rigid member located within the rear portion and having its front end pivotally supported therein, a guiding plane pivotally secured to the rear end of said rotating rigid member, a hand lever pivotally secured to the rotating rigid member located

in the rear portion, and a link connection between the guiding plane and hand lever, and a guiding plane pivotally secured to said rotating member and capable of being 65 thrown into operative and inoperative position by the rotation of the rotating rigid member mounted in the tubular portion.

3. An aeroplane comprising a body portion, a tubular rear portion, a rotating member located within the rear portion, a steering plane pivotally secured to said rotating member, a hand lever pivotally secured to said rotating member, a pair of links pivotally secured to the hand lever and steering 70 plane, a guiding plane passing through the wall of the tubular portion and pivotally secured to the rotating members, said guiding plane adapted to be withdrawn out of operative position and extend into operative 75 position by the rotation of the rotating member.

4. An aeroplane comprising a tubular rear portion, a support within the tubular rear portion, a steering plane mounted in the rear 85 end of the tubular portion and capable of a vertical and rotary movement, a rotating member mounted in the tubular portion, a connection between said member and steering plane, a universal connection between 90 said member and the support mounted in the tubular portion, a pivoted hand lever carried by the rotating member, a guiding plane pivotally secured to the rotating member, and stop arms carried by the guiding plane. 95

5. An aeroplane comprising a rear tubular portion, a rigid skeleton member having one of its ends mounted for rotation within said rear tubular portion, a yoke pivotally and adjustably carried by the opposite end of 100 said rigid skeleton member, a guiding plane carried by said yoke, a hand lever pivotally secured to the forward end of the rigid skeleton member, a link disposed on opposite sides of the rigid skeleton member and having its ends pivotally secured to the yoke and hand lever, and a guiding plane mounted within an opening formed in the rear tubular portion and pivotally connected to the rigid skeleton member and capable of being operated upwardly and downwardly by the rotation of the rigid skeleton member and stop arms carried by said guiding plane to limit the downward movement thereof. 110

In testimony whereof, I have signed my 115 name to this specification in the presence of two subscribing witnesses.

GEORGE ORTGIER.
